APPARATUS FOR SHAPING TUBING

Walter P. Hill, Detroit, Mich., assignor, by mesne assignments, to Calumet and Hecla Consolidated Copper Company, Calumet, Mich., a corporation of Michigan

Application April 27, 1942, Serial No. 440,712

5 Claims. (Cl. 113—52)

This invention relates generally to tools for shaping stock and refers more particularly to improvements in tools for reducing tubular stock.

One of the principal objects of this invention is to provide a reducing tool having a cavity for receiving a length of tubular stock and having means enabling numerous different shapes to be imparted to the stock as it is advanced through the cavity.

Another object of this invention is to provide a reducing tool having relatively adjustable parts enabling the extent of reduction of the stock to be readily varied. As a result of this feature, the cross sectional area of the stock and, consequently, the shape of the stock may be varied within wide limits with the same tool.

A further object of this invention is to provide an adjustable reducing tool of the character set forth above having means for initially heating the stock by exerting a reducing pressure continuously around the entire circumference of the stock to render the latter easily workable and having means for further reducing the stock by exerting a reducing pressure on a continuous area of the stock extending over a portion of the circumference of the stock while leaving the remaining portion of the stock free to deform in response to the reducing pressure.

A tool of the above general type not only enables the cross sectional area of the stock to be varied during the reducing operation but also enables the stock to be maintained in a plastic or easily workable condition and thereby controls the distribution of the stock so that there will be a uniform or controlled distribution resulting in the desired configuration and stock thickness in the completed article.

The foregoing, as well as other objects, will be made more apparent as this description proceeds, especially when considered in connection with the accompanying drawings, wherein:

Figure 1 is a top plan view of a tool constructed in accordance with this invention;

Figure 2 is an enlarged longitudinal sectional view through the tool shown in Figure 1 and illustrating a length of stock in the tool;

Figure 3 is a cross sectional view taken substantially on the line 3—3 of Figure 2;

Figure 4 is a diagrammatic end elevation of the tool showing the parts thereof in one extreme position of adjustment;

Figure 5 is a view similar to Figure 4 showing the parts of the tool in another extreme position of adjustment; and

Figure 6 is a fragmentary sectional view through a length of tubular stock shaped by the tool shown in Figures 1 to 4, inclusive.

Referring now more in detail to the drawings it will be noted that the tool selected for the purpose of illustrating this invention comprises two relatively rotatable parts 10 and 11. The part 10 has a recess or bore 12 concentric with the axis 13 of the tool and the part 11 also has a recess or bore 14 which cooperates with the bore 12 to form a cavity 15 through which a length of tubular stock 16 is adapted to be extended upon relative axial movement of the tool and stock toward each other. The mechanism for relatively axially moving the stock and tool toward each other is not shown herein because it is evident that any one of a large number of mechanisms may be used for this purpose.

Upon reference to Figure 2 it will be noted that the tool part 11 is eccentrically mounted on the tool part 10 for rotation about the axis 17, shown in Figures 3, 4 and 5 as being offset laterally from the tool axis 13. In detail, the tool part 11 is rotatably supported in a recess 18 formed in the rear end of the tool part 10 and having an inner cylindrical wall concentric with the axis 17 to provide a bearing support for the tool part 11. The bore 14 through the tool part 11 is eccentrically located with respect to the axis 17 of rotation of the tool part 11 and the axis 19 of the bore 14 is spaced laterally from the axis 17 a distance equal to the distance between the axis 17 and the axis 13. It follows from the above that the axis 19 of the bore 14 through the tool part 11 rotates around the axis 17 of the part 11 upon relative rotation of the tool parts.

The above construction is such that when the parts of the tool are in the extreme position of adjustment shown in Figure 4, the bore 14 in the tool part 11 is in alignment with the bore 12 in the tool part 10. The other extreme relative position of the tool parts is shown in Figure 5 wherein it will be noted that the bore 14 is offset from the bore 12 to such an extent that the wall portion 20 of the bore 14 intersects the axis 13 of the tool. It will also be noted from Figure 2 of the drawings that the wall portion 20 of the bore 14 is tapered outwardly at the entrant end of the bore 14 to form a pressure applying surface 21 for engaging the stock leaving the adjacent end of the bore 12.

The maximum reduction of the stock is accomplished when the parts of the tool are in the relative positions of adjustment shown in Figure 5.

In fact, when the tool parts are in the relative positions shown in this figure, the maximum area of the pressure applying surface is exposed to the delivery end of the bore 12 and the end of the stock is completely closed. As the tool parts are relatively adjusted from the position shown in Figure 5 to the position shown in Figure 4, the area of the pressure applying surface 21 exposed to the delivery end of the bore 12 is gradually reduced and the degree of reduction of the stock is correspondingly reduced. Thus, the extent of reduction of the stock may be readily varied within wide limits by merely relatively rotating the tool parts. In the present instance the part 11 is rotated relative to the part 10 by a lever 22 operatively connected to the part 11 in a manner to be more fully hereinafter set forth.

Referring again to Figures 4 and 5 of the drawings, it will be noted that as the tool part 11 is rotated relative to the tool part 10 from the position thereof shown in Figure 4 toward the position shown in Figure 5, the portion of the bore 14 opposite the pressure applying surface 21 provides a relief A of sufficient size to enable the stock to freely deform in response to the reducing pressure applied by the surface 21.

The stock is initially heated sufficiently to enable the same to be easily worked by applying a limited reducing pressure on the stock throughout its circumference and this is accomplished by reducing the bore 12 at the delivery end of the latter. This reduced portion is indicated in Figure 2 of the drawings by the reference character 26.

The tool and stock are not only relatively axially moved toward each other to effect the reducing operation but are also relatively rotated about the axis 13 of the tool. Any suitable mechanism may be provided for rotating either the stock or the tool and, therefore, no specific means is shown for this purpose. In the event it is desired to rotate the tool parts the latter are supported in a revoluble holder or housing 24 in such a manner that rotation of the housing effects a corresponding rotation of both tool parts.

As shown in Figure 2, the front end portion of the housing has an opening therethrough of sufficient dimension to receive the tool part 10 and the opposite or rear end of the housing has a reduced opening registering with the delivery end of the bore 14 in the tool part 11 to enable passage of the stock. The surface of the housing surrounding the opening through the front end thereof is concentric with the tool axis 13 and has a bearing engagement with the outer surface of the tool part 10. The part 10 is held against rotation relative to the housing by bolts 27 passing through a radially outwardly extending flange 28 on the front end of the tool part 10 and threaded into the front wall of the housing. The rear end of the tool part 11 abuts the rear wall of the housing and is adjustable relative to the part 10 by manipulating the lever 22 as will be described.

The lever 22 which as specifically shown is in the form of a yoke is engageable with an annular groove formed by spaced ribs 29a on a slide 29 splined on the housing 24 for movement axially of the latter said slide having a groove 30 formed in the inner surface thereof for receiving a pin 31. The pin 31 extends radially outwardly from the tool part 11 and projects into the groove 30 through registering segmental slots 32 in the adjacent walls of the tool part 10 and the housing 24. The groove 30 is helical or, in other words,

is inclined with respect to the axis of rotation of the tool and the angle of inclination is such that when the slide 29 is reciprocated, the side walls of the groove exert a camming action on the pin 31 sufficient to rotate the tool part 11 relative to the part 10. As a result, the extent of reduction of the stock passing through the reducing tool may be varied during rotation of the tool to form the stock with inwardly or outwardly tapering portions.

Operation

The first step in the operation of the reducing tool is to rotatably adjust the part 11 relative to the part 10 to the extent necessary to obtain the desired degree of reduction of the length of tubular stock to be reduced. Assuming that it is desired to partially reduce the stock, the part 11 is rotated to a position between the two extreme positions shown in Figures 4 and 5. The tool and the length of stock to be reduced are then relatively axially moved toward each other to extend the end of the stock into the bore 12 in the tool part 10. As the stock is advanced along the bore 12 either the stock or tool is rotated about the axis 13 and the stock is engaged with the reduced portion or heat ring 25 at the delivery end of the bore 12.

The reduced portion 25 exerts a reducing pressure continuously around the circumference of the stock and heats the latter sufficiently to enable the same to be readily worked. Continued advancement of the stock along the bore 12 causes the end of the stock to engage the tapered surface 21 at the entrant end of the bore 14 through the part 11 and this tapered surface reduces the stock to a diameter depending upon the area of the surface registering with the delivery end of the bore 12. As the stock is reduced by the surface 21, the excess stock resulting from thermal expansion and reduction in cross sectional area is free to deform into the relief portion A provided in the bore 14 opposite the surface 21. As a result, the stock is worked sufficiently during the reducing operation to maintain the same in a plastic state and, at the same time, is prevented from overheating. In addition, the above construction provides for accurately controlling distribution of the stock and renders it possible to form the stock to the desired configuration and wall thickness. This is accomplished by movement of the lever 22 (which has a suitable fulcrum not shown) and the longitudinal movement of the slide 29 which through the helical groove 30 and pin 31 imparts a rotary movement to the member 11. Such rotation will move the tapered surface 21 towards or away from the axis of rotation of the tool thereby imparting to the work the desired contour.

In Figure 6 of the drawings I have shown a length of tube B capable of being formed by the reducing tool described above and having axially spaced portions of different cross sectional area. These portions are formed by relatively rotatably adjusting the tool parts at the proper intervals in the reducing cycle. Particular attention is directed to the fact that regardless of the variations in contour of the tube B, the wall thickness is substantially uniform and this is the result of controlling the distribution of the stock in the manner previously pointed out. In the event it is desired to completely close one end of the stock, the tool parts are relatively rotated to the extreme position shown in Figure 5 wherein the line of intersection between the tapered surface

21 and adjacent side wall of the bore 14 passes through the axis of the bore 12.

What I claim as my invention is:

1. A forming tool for reducing stock comprising a part having a bore therethrough extending in the general direction of the axis of the tool for receiving a length of stock and having a portion at the delivery end restricted for exerting a reducing pressure on the stock to heat the latter, a second part eccentrically mounted with respect to the axis of the bore in the first part and positioned at the delivery end of the bore, said second part having a bore therethrough provided with a portion at the entrant end tapered outwardly to provide a pressure applying surface for engaging the stock leaving the delivery end of the first bore, the axis of the second bore being laterally offset from the axis of the second part a distance approximating the distance between the axis of the second part and the axis of the first bore 20 whereby relative rotation of the parts moves the second bore from a position in alignment with the first bore to positions wherein more or less of the area of the pressure applying surface registers with the delivery end of the first bore and wherein the space in the second bore opposite the pressure applying surface forms a relief area into which the stock freely deforms as a result of the reducing pressure.

2. A forming tool for reducing stock comprising a part having a bore therethrough for receiving the stock and having a recess at the delivery end of the bore, the axis of the recess being offset laterally from the axis of the bore, a second part mounted in the recess for rotation about the axis of the recess and having a bore therethrough eccentrically located with respect to the axis of rotative movement of the second part, the axis of the second bore being so located with respect to the axis of the second part that in one relative rotative position of the parts the second bore assumes a position in alignment with the axis of the first bore, said second bore having a portion of one side wall at the entrant end tapered outwardly, and means for relatively rotating said parts to register more or less of the area of said tapered portion with the delivery end of the first bore to thereby correspondingly vary the reducing pressure applied to the stock.

3. A forming tool for reducing stock comprising a part having a bore therethrough for receiving the stock, a second part supported at the delivery end of the bore for rotation about an axis offset laterally with respect to the axis of the bore and having a bore therethrough cooperating with the first bore to form a cavity, the axis of the second bore being offset laterally from the

5 axis of the second part a distance approximating the distance between the axis of the second part and the axis of the first bore whereby in one extreme relative rotative position of the parts the bores are in alignment and in the other extreme relative rotative position of said parts one side wall portion of the second bore intersects the axis of the first bore, said side wall portion of second bore being tapered outwardly at the entrant end 10 of the second bore to provide a stock reducing surface, and means for relatively rotating said parts between the two extreme positions aforesaid to register more or less of the area of reducing surface with the delivery end of the first bore 15 to thereby control the extent of reduction of the stock and to also provide a relief area in the second bore opposite said tapered wall portion to enable the stock to deform freely in response to the reducing operation.

4. A forming tool comprising a rotary hollow member having an entrance for the stock and a concentric circumferentially contracted portion in rear of said entrance for reducing and heating the stock when relatively advanced therethrough, a second member mounted on the aforesaid member in rear of said contracted portion to be rotatably adjustable about an axis eccentric to the axis of rotation of said tool, said second member having an eccentric recess extending therethrough with the surface on one side of said recess longitudinally tapered, and means for rotatably adjusting said second member relative to said first member during the continued rotation of the tool whereby said tapered surface is moved 25 towards or from the axis of rotation to correspondingly fashion the stock during continued relative advancement thereof.

5. A forming tool comprising a rotary hollow member having an entrance for the stock and a concentric circumferentially contracted portion in rear of said entrance for reducing and heating the stock when relatively advanced therethrough, a second member mounted rotatably adjustable about an axis eccentric to the axis of rotation of said tool, said second member having an aperture therethrough with the surface on one side thereof inclined to said axis of rotation to exert an inward pressure on a segment of the surface of the stock leaving another segment thereof free for expansion, and means for rotatably adjusting said second member relative to said first member during the continued rotation of the tool whereby said inclined surface is moved towards or from the axis of rotation to correspondingly fashion the stock during the continued relative movement thereof.

WALTER P. HILL.
